FIG. 1

1

2,847,164

VALUE APPROXIMATION MECHANISM

Grant C. Ellerbeck, San Leandro, Calif., assignor to
Friden, Inc., a corporation of California

Application October 30, 1953, Serial No. 389,375

7 Claims. (Cl. 235—144)

This invention relates to calculating machines and is concerned more particularly with an improved register clearing mechanism particularly adapted to reset preselected orders of the register to a predetermined value, such as "5."

It is a general object of my invention to provide an improved means for completing calculations in desired orders to the nearest cent, and to perform this operation in such a way that the total, or accumulated totals, will be correct to the nearest cent.

In many calculations it is desirable to multiply one value by another, in which one of the values is a fraction of a cent, so that the product secured will be registered in fractions of a cent. Examples of such work are payroll calculations in which it is necessary to multiply a rate paid for the work by the number of hours' work in order to obtain the amount to be paid to each employee, in which the rate may include a fraction of a cent. Another example is in billing operations in which the price per item will be given in fractions of a cent so that the total price to be paid will also include similar fractions. It is necessary to complete the calculation to the nearest cent, and it is very desirable that this be done automatically so as to avoid mental operations on the part of the calculating machine operator. One of the most convenient ways of performing this "rounding off" operation to the nearest half-cent is to insert a value of "5" in the order next below the lowest desired value (for example, in the order below the "cent" order when values are accumulated to the closest cent) at the time of clearing the register. If the values added thereto are less than half a unit (five mills, or a half-cent, in the example suggested), the value in this lowest order will be no greater than "9" and no tens-transfer will occur into the next higher or cents order. On the other hand, if the value added to the "5" is "5" or more, then the dial in the lowest, or mills, order will pass through the "9" to "0" position and will thus initiate a tens-transfer into the next higher, or cents, order. Thus, in rounding off to the closest cent by this method, if the mills accumulated are less than "5," the cents dial reads the accumulated number of cents; but if more than five mills are accumulated, those values added to the five mills initially inserted are effective to operate a tens-transfer into the cents order and thus register one cent more than the totals accumulated in that order. Thus, in either situation, the total is rounded off to the closest cent, automatically.

It is therefore a particular object of my invention to provide an improved mechanism for inserting the half-cent, or five mills, in any one of a number of preselected orders of the calculating machine and thus accumulate values to the closest cent.

It is another object of my invention to provide a calculating machine in which the resetting operation serves to enter one or more half-cent, or other half-unit, values in selected orders of the accumulator.

2

Another object of the present invention is to provide a resetting, or clearing, mechanism which will enter predetermined values, such as "5," in certain selected orders of the accumulator as part of the resetting, or clearing, operation.

A further, and an important, object of the present invention is to provide a half-cent mechanism which does not require the conventional disabling of the tens-transfer mechanism during the clearing operation.

10 These and other objects of the present invention will be apparent from the following description of a preferred embodiment thereof, as illustrated in the accompanying drawings in which:

Fig. 1 is a partial plan view of a portion of the accumulator register with which my invention is associated, in the normal, or cleared, position.

Fig. 2 is a view of the half-cent mechanism of my invention in the cocked position, which occurs at the end of the clearing stroke and prior to the return of the clearing mechanism to its normal inoperative position; and also shows details of the clearing rack and gear with which my invention is associated.

My invention is illustrated as embodied in the accumulator register of the type shown and disclosed in the patent to Carl M. Friden of January 28, 1941, No. 2,229,889. Generally, such calculating machines include a selection mechanism, actuating means, and various control mechanism for performing various operations such as addition, subtraction, multiplication and division. Such mechanisms are conventional, and are particularly disclosed in the patent referred to, so that their disclosure is not necessary to an understanding of the instant invention. Such machines generally include a shiftable carriage in which an ordinarily arranged accumulator is mounted. In the patent referred to, the carriage includes a hollow frame bar 10 which is slidably mounted in the calculating machine and which can be moved to any preselected ordinal position by means not pertinent and not shown. A plurality of ordinarily arranged accumulator dials 11 are rotatably mounted in the carriage frame 10, as by mounting upon dial shafts 12 which are journaled in the top and bottom of the frame bar. The lower ends of the dial shafts 12 carry a driving gear, not shown, rigidly secured thereto, which gears are driven by the machine to accumulate values in the register dials 11. The register dials are conventionally centralized in a full-value position by a conventional centralizing means, not shown, and generally are provided with a tens-transfer mechanism which is of no interest in the present invention.

It is conventional to provide means for clearing the register dials 11 to "0" when desired. In my preferred embodiment the clearing means comprises a pair of racks 15 mounted for longitudinal movement in the interior of the frame bar 10, each of said racks including a plurality of teeth 14 alternately arranged with respect to a blank portion 13, as shown in Fig. 2. The teeth and blanks of the racks are staggered on the two racks 15 so that they may cooperate with mutilated gears 16 mounted on the respective shafts 12, the mutilated clearing gears 16 being vertically, or axially, offset along the shafts 12 so that alternate gears register with the upper rack and the others with the lower rack 15. Each such gear is mutilated by the removal of two teeth, as shown in Fig. 2, and the mutilated portion is in the position shown in this figure when the associated dial stands at "0."

To perform the resetting, or clearing, operation the racks 15 are moved laterally of the machine (lengthwise of the carriage frame 10), whereby the rack portions thereof engage the clearing gears 16 which are displaced

from the "0" position and rotate them and their associated shafts and dials to the "0" position, in which position further rotation is blocked by a blocking means to be described shortly. It is conventional in machines of this kind to provide various means for operating the clearing racks, such as the manually operated post 18 shown in Fig. 1 which is rigidly mounted in the racks 15. The clearing racks 15 may also be operated by a conventional power means, not shown, which acts through an interponent, not shown, to move the post 18 when desired.

In order to insure stopping of the numeral wheels, or dials, at "0" without overthrow, a stop slide 25 is slidably mounted upon the upper surface of the carriage frame 10. The stop slide is provided with a projection, or shoulder, 26 for each order of the accumulator, which shoulders, or fingers, are adapted to move into the path of travel of an abutment 28 formed on a stop cam 27, one of which is mounted on each of the dial shafts 12 immediately adjacent the upper surface of the frame bar 10. The stop slide 25 is moved in synchronism with the initial movement of the racks 15 by any suitable means. A conventional means normally used with the machine of the patent above-mentioned comprises a bellcrank 31 pivotally mounted on the right-hand end of the frame 10 by any suitable means, such as screw 32. This bellcrank has a rightwardly extending arm which is provided with a cam surface 34 engaging a roller 29 mounted on post 18. Thus, the initial movement of the clearing rack 15 toward the right, which occurs at the start of a clearing operation, causes the roller 29 to engage the cam face 34 of the bellcrank, thereby rocking the bellcrank (clockwise in Fig. 2), and will hold it in the rocked position until the clearing rack 15 returns to its inoperative position shown.

The rearwardly extending arm of the bellcrank 31 is bifurcated, as at 36, to embrace a pin 37 rigidly secured to the right-hand end of the stop slide 25. Operation of the clearing rack 15 thus causes the roller 29 to rock the bellcrank 31, which, through the pin-and-slot arrangement 37, 36 moves the stop slide 25 toward the right. In this position the shoulders, or fingers, 26 lie in the path of travel of the abutments 28 of stop cams 27, so that when the respective shafts are rotated to their "0" position, the shoulders 28 abut against the end of the fingers 26, thereby blocking further rotation of the dial shafts 12.

The mechanism heretofore described is conventional and is not claimed herein. My invention comprises mechanism by means of which the conventional clearing mechanism heretofore described may be operated in order to insert a preselected value, such as "5," in selected orders at the will of the operator, when the clearing mechanism is operated. The mechanism of my invention will now be described.

My invention embodies the principle of returning the selected dials 11 from the "0" position, in an additive direction after the clearing operation. It will be noted that the dials are returned from their adjusted position to "0" in a subtractive (clockwise in the drawing) direction during the clearing stroke, so that in my invention the register dials do not pass through the tens-transfer or "9" to "0" position. Therefore it is unnecessary, in my invention, to disable the tens-transfer mechanism as is conventional in most half-cent mechanisms.

In the preferred form of my invention I mount a mutilated gear 77 on the selected dial shafts 12, preferably immediately above the stop cam 27. The gear 77 preferably has four teeth 78 which are followed by a flattened surface 79 which operates as a Geneva block, when the gear rotates in an additive, or counterclockwise, direction.

A rack 85 lies in the plane of the gear 77, and is pivotally mounted on a stud 86 carried by a bracket 87 riveted to, or otherwise rigidly mounted on, the stop

slide 25. This rack includes an arcuate portion provided with teeth 84 adapted to mesh with the teeth 78 of the mutilated gear 77. The rack 85 is biased in a clockwise direction (to rotate the dial in an additive, or counterclockwise direction) by means of a spring 88 tensioned between an aperture, or spring seat, 89 in the rack and a stud 90 mounted on the stop bar 25. The rack 85 is preferably formed with a shoulder 109 which operates as a Geneva wheel in cooperation with the flat portion 79 of the gear 77, which acts as a Geneva block, thereby blocking overthrow of the gear 77 when the rack and gear are engaged.

The rack 85 has a depending stud 91 mounted thereon which is embraced by a slot 96 in the left end of a link 95 pivotally mounted on the clearing post 18. When the post 18 is moved to the right to initiate a clearing operation, the link 95 moves with it. At the start of such movement of the post 18 and clearing racks 15, the stop rack 25 moves a slight distance to the right and then stops as the roller 29 passes along the straight face, or cam edge, 34 of the bellcrank 31. The slight movement of the stop slide 25 to the right moves the rack 85 from a meshing position with the gear 77, the rack 85 remaining stationary on its axis during such movement of the stop slide 25. However, after the stop slide has stopped its movement the continued movement of the post 18 moves the link 95 continuously to the right. Such movement of the link 95 relative to the stop slide 25 causes the end of slot 96 to engage stud 91 on the rack, and thereafter rotates the rack approximately 90 degrees against the urging of its spring 88. As the rack has been moved away from its associated gear 77, such rotation of the rack will have no effect upon gear 77 or its related shaft 12.

There is a latch arm 100 associated with the rack 85, which latch arm can be pivotally mounted in any suitable manner, such as upon stud 101 secured to the stop slide 25. The latch arm 100 is normally biased into engagement with the rack 85 (in a counter-clockwise direction in the drawing) by any suitable means, such as spring 102 tensioned between an aperture, or spring seat, 103 in the latch arm and a stud 104 on the top surface of the carriage frame bar 10. Normally, however, the latch member 100 is rocked against the tension of its spring 102 to disengage the rack 85 by any suitable means, such as by a bracket 105 mounted on the rear wall of the frame bar 10 engaging a shoulder 106 on the latch member 100. During the clearing operation, however, the stop slide 25 moves to the right relative to the frame bar 10, so that the latch member can rock counter-clockwise whereupon its nose 107 can engage in latching notch 108 of the rack 85. Thereafter, just before the end of the return stroke of the clearing rack 15, the stop slide 25 moves to the left. At this time the shoulder 106 of the latch again engages the bracket 105, rocking the latch 100 clockwise and releasing rack 85. The return movement of the stop slide 25 also returns the rack 85 into engagement with the gear 77 on the associated dial shaft. Thus, the rocking of latch 100 releases the rack 85 to the force of its spring 88, which pulls the rack 85 (clockwise in the drawing) and rotates the mutilated gear 77 from the "0" position shown in Fig. 2 to the "5" position shown in Fig. 1. In this position overthrow of the gear is prevented by the shoulder 109 on the rack registering with the flat portion 79 of gear 77, the two cooperating to form a Geneva stop.

I prefer that the operation of the latch 100 be under the selective control of the operator and for this purpose provide a cam means for rocking the latch 100 to an inoperative position, if desired. One preferred means comprises a cam 120 rigidly mounted on a shaft 121 journalled in the upper face of the carriage frame bar 10. Preferably, the shaft 121 projects through a slot 122 in the stop bar 25 and can be rotated either to an operative

or an inoperative position by means of a conventional twirler (not shown) mounted on the upper end thereof. The cam can be held in either adjusted position by any suitable detent means, such as spring clip 123 mounted on the rear face of the carriage frame bar 10. Cooperating with the cam 120 is a cam face 124 formed on the right-hand edge of the latch member 100, so that if the cam is rotated 180 degrees from the position shown in Figs. 1 and 2 the cam will engage the cam face 124 immediately before the end of the stroke of the stop bar 25, and thereby rock the arm 100 slightly so that it cannot engage the rack 85. When this is done, the rack 85 will not be latched by the latch 100 and is therefore free to return to its normal position under the bias of spring 88 as the link 95 moves to the left. It will be recalled that there is a considerable stroke of the clearing rack 15 and its operating post 18 after the stop slide 25 ceases to move and on the return stroke, the post and the link will have returned a considerable distance before the stop slide 25 is free to return to its normal position. Therefore, on the return stroke, the post 18 and link 95 will travel a considerable distance to the left, and will permit the rack 85 to be rotated clockwise to its normal angular position, before the stop slide 25 begins to return to its normal position. During such rotational movement of the rack 85 it lies to the right of gear 77 and therefore does not rotate it in any manner. By so rotating the cam 120 through an arc of 180 degrees and thus preventing the latching of the rack 85 by arm 100, the rack will have returned to its normal position shown before it can engage the mutilated gear 77.

It will thus be obvious that if the cam 120 is rotated away from the latch 100, as shown in Figs. 1 and 2, the latching arm 100 will be free to engage the rack 85. In that event the release of the rack 85 will be delayed until after the stop slide 25 has moved to the left to cause the rack 85 to engage the gear 77. In this event the gear 77, and consequently its dial 11, will be rotated through an angle of 180 degrees, or to the "5" position, without the dial passing through the tens-transfer, or "9" to "0," position. On the other hand, if the cam 120 is rotated 180 degrees, it will engage the face 124 of latch member 100, rotating the latter slightly so that it cannot engage and latch the rack 85. In that event the rack will return to its normal clockwise position as soon as the clearing rack and post 18 return a slight distance toward their normal left-hand position. In that event the rack is rotated, before it can engage the gear 77. When the rack 85 has been rotated to this extreme position, the cutaway portion 110 permits rotation of the gear 77 without engaging the rack, so that the rack will not interfere with digitation in this order of the machine.

I claim:

1. In combination with a calculating machine register having a plurality of rotatable dials and clearing means for rotating said dials to a "0" position: a mutilated gear connected to a selected one of said dials, gear means movable to a first position to engage said mutilated gear and to a second position to disengage the same, means operated simultaneously with operation of said clearing means for moving said last-mentioned gear means to said second position during operation of the clearing means to return the dials to "0" position and for causing said gear means to move to said first position to engage said mutilated gear after said dials have returned to their "0" positions, and means for rotating said gear means after such engagement.

2. In combination with a calculating machine register having rotatable dials, a mutilated gear connected to each such dial for rotation therewith, means for rotating said mutilated gears to a "0" position, and means for operating said rotating means: a second mutilated gear connected to each of selected ones of said dials, normally disengaged gear means movable to engage said second mutilated gears, means operated simultaneously with said

rotating means for moving said last-mentioned gear means into engagement with said mutilated gears after operation of said rotating means has rotated the first mentioned mutilated gears to their "0" positions, and means for rotating said gear means during such engagement.

3. In a calculating machine the combination which comprises a plurality of rotatable register dials, a mutilated gear connected to each such dial for rotation therewith, a reciprocable rack for rotating said mutilated gears to a "0" position, means for operating said rack, a second mutilated gear connected to a selected dial, normally inoperative drive means engageable with said second gear, means for moving said drive means out of engagement with said mutilated gear during movement of the clearing rack in one direction and for causing it to engage said gear during movement in the other direction, and means for operating said drive means during such engagement.

10 4. In a calculating machine the combination which comprises a rotatable register dial, a mutilated gear connected to such dial for rotation therewith, a reciprocable rack for rotating said mutilated gear to a "0" position, means for reciprocating said rack, a second mutilated gear connected to said dial, mutilated drive gear means engageable with said second mutilated gear, means for moving said drive gear means away from engagement with said second mutilated gear during movement of the clearing rack in one direction, means operated by said rack for rotating said drive gear means from its original angular position during such movement of said rack, a latch for retaining said drive gear means in its rotated position, resilient means for returning said drive gear means to its original angular position, means controlled 15 by the rack during movement of said rack in the other direction for causing the drive gear means to engage said second mutilated gear, and means for releasing said latch after such engaging.

30 5. The combination of claim 4 comprising also a manually set means for selectively enabling or disabling said latch.

6. In combination with a clearing mechanism for a calculating machine register having a plurality of rotatable dials, a mutilated gear connected to each such dial for rotation therewith, a rack for rotating said mutilated gears to a "0" position, and means for operating said rack through a clearing stroke during which the dials are returned to their "0" positions and an idle return stroke: a setting gear member mounted on a predetermined dial, an arcuate rack adapted to cooperate with said gear member, means for moving said arcuate rack away from said gear member during the clearing stroke of said clearing rack, means biasing said arcuate rack in one direction, means for rocking said arcuate rack in the opposite direction during the clearing stroke of said clearing rack, means for selectively latching said arcuate rack in its rotated position, means for moving said arcuate rack into mesh with said gear member during the return stroke of said clearing rack, and means for releasing said latching 45 means at approximately the end of the return stroke.

7. In combination with a clearing mechanism for a calculating machine register having a plurality of rotatable dials, a mutilated clearing gear mounted on each such dial for rotation therewith, a rack for rotating said mutilated gears to a "0" position, a stop slide operated simultaneously with the initial movement of said rack for blocking overthrow of said dials, and means for operating said rack and said stop slide through a clearing stroke during which the dials are returned to their "0" positions 50 and an idle return stroke: a gear member mounted on a predetermined dial, a second rack rotatably mounted on said stop slide and adapted to engage said gear member, said second rack being mounted on said slide in a manner to be moved away from said gear member by the 55 operation of said slide during the clearing stroke of said

first rack and said stop slide and to engage said gear member on the return stroke of said rack and slide, means biasing said second rack in one direction, means operated by said clearing rack for rocking said second rack in the opposite direction during the clearing stroke of said clearing rack, means for selectively latching said rack in said rocked position, and means for releasing said latching means at the end of the return stroke of said stop slide.
